United States Patent Office

Des. 224,754
Patented Sept. 12, 1972

224,754

XEROGRAPHIC LABEL MAKING MACHINE

John F. Zinni, Rochester, N.Y., assignor to
Xerox Corporation, Stamford, Conn.

Filed Apr. 5, 1971, Ser. No. 131,007

Term of patent 14 years

Int. Cl. D16—03

U.S. Cl. D61—1

FIG. 1

FIG. 2

FIG. 4

FIG. 3

FIG. 5

FIG. 6

FIG. 1 is an isometric view of a xerographic label making machine showing my new design;

FIG. 2 is a top plan view thereof;

FIG. 3 is a front elevational view thereof;

FIG. 4 is a right side elevational view thereof;

FIG. 5 is a left side elevational view; and

FIG. 6 is a rear elevational view thereof.

I claim:

The ornamental design for a xerographic label making machine, as shown.
